UNITED STATES PATENT OFFICE.

**JOHN BALLANCE, OF NEW YORK, N. Y., ASSIGNOR OF ONE-HALF TO JOHN A. PRESSL,
OF NEW YORK, N. Y.**

LIQUID-CONTAINER.

1,071,859.

Specification of Letters Patent.

Patented Sept. 2, 1913.

Application filed April 12, 1913. Serial No. 760,713.

To all whom it may concern:

Be it known that I, JOHN BALLANCE, a citizen of the United States, residing at New York, in the county of New York and State 5 of New York, have invented certain new and useful Improvements in Liquid-Containers; and I do declare the following to be a full, clear, and exact description of the invention, such as will enable others skilled in 10 the art to which it appertains to make and use the same.

This invention relates to improvements in liquid containers and particularly to bottles or similar receptacles.

15 One object of the invention is to provide a liquid container constructed of paper, cardboard, celluloid or similar pliable material pressed or crimped into the desired shape and coated with a suitable substance
20 to render the same fluid-tight and sanitary.

Another object is to provide a container of the character described which will be strong and durable in construction, light in weight, efficient and reliable in use and which may be employed for holding any kinds of liquids.

In the accompanying drawings: Figure 1 is a perspective view of the sheet of fabric from which the container is formed; Fig. 2 is a sectional perspective view illustrating the manner in which the upper portion of the sheet is crimped and pressed into shape to form the top of the body and neck of a bottle; Fig. 3 is a vertical section of the body of the bottle with the bottom and cap in position to be engaged therewith; Fig. 4 is a similar view of the frusto-conical shaped casing which covers the upper crimped portion of the body of the bottle; Fig. 5 is a similar view of the cylindrical lining for the inner surface of the crimped neck of the bottle; Fig. 6 is a similar view of the casing which covers the outer surface of the crimped neck of the bottle; Fig. 7 is a side view of the bottle complete; Fig. 8 is a central vertical section of the complete bottle; Fig. 9 is a horizontal section through the upper portion of the body of the bottle taken on the line 9—9 of Fig. 8; Fig. 10 is a similar view through the neck of the bottle taken on the line 10—10 of Fig. 8; Fig. 11 is a similar view taken through the body on the line 11—11 of Fig. 8; Fig. 12 is a detail vertical section of the upper portion of the neck of the bottle illustrating a slightly different

form of cap or closure; Fig. 13 is a similar view of the lower end of the body of the bottle illustrating a slightly different arrangement of bottom; Fig. 14 is a view similar to Fig. 13 showing another modified construction and arrangement of bottom.

In the present instance the invention is shown in the shape of a bottle having a comparatively broad short neck and wide mouth. It will be obvious, however, that the container may be of any other suitable shape or form. In forming the bottle I provide a sheet of fabric F of suitable size and shape and which may be paper, woven fabric, celluloid or any other pliable material. In the present instance the bottle is represented as being formed from paper and when thus formed the sheet of paper has applied to one side thereof a covering or backing B of muslin, calico, cheese cloth or the like which is provided to strengthen and brace the paper whereby the same will be enabled to withstand more pressure to which the same may be subjected by heavy liquids placed in the container. 65 70 75 80

In forming the bottle the sheet of fabric F is bent to form a tube 1 and has its edges overlapped and glued or cemented together to form a fluid-tight joint. In forming this joint the overlapping edges of the sheet of fabric are preferably shaved down or tapered gradually to a fine edge as shown at a in Fig. 11 of the drawings so that the overlapped edges of the fabric are flush or do not form a projection on either the inner or outer side of the body or neck of the container. After the tube 1 has thus been formed the upper portion thereof is crimped and pressed inwardly by any suitable means for forming the frusto-conical shaped upper portion 2 and the cylindrical neck 3 of the bottle. After being thus formed or crimped the frusto-conical shaped upper portion of the body of the bottle is preferably covered on its outer side by a frusto-conical shaped casing 4 which is slipped down over the neck and crimped upper portion of the body and is secured thereto in any suitable manner. The outer side of the crimped neck 3 of the bottle is also preferably covered by a tubular cylindrical casing 5 while the inner surface of the crimped neck is covered by a lining 6. By thus covering the crimped upper portion of the body and the neck of the bottle the crimpings or irregu- 110

2

larities of these parts are covered and a smooth surface provided which gives the finished bottle a more attractive appearance besides making the same more sanitary as when the crimpings are covered dirt is prevented from accumulating therein. The bottom 7 of the body is also formed of paper or other suitable fabric and is pressed into the form of a shallow cup which may be inserted into the lower end of the body of the bottle as shown in Fig. 8 of the drawings or may be engaged with the outer side of the lower end of the body as shown in Fig. 13 of the drawings. The bottom when applied 10 in either manner described is glued or otherwise securely fastened to the body. When the bottom is inserted into the lower end of the body of the bottle an outer fabric covering 8 is preferably applied to the outer side of the bottom and has its edges brought up around the outer side of the lower end of the body and glued or securely fastened thereto as clearly shown in Fig. 8 of the drawings. The bottom 7 is preferably 15 braced or made more rigid by a series of concentric beads or corrugations 9 which are pressed into the bottom from the inner side thereof as shown.

The upper edges of the crimped portion 30 of the neck, the outer casing member 5 and the lining 6 are preferably covered and pro-

35 tected by a strip of fabric 10 which is glued or pasted over said edges and has its edges lapped down over and secured to the outer surface of the casing 5 and lining 6 as clearly shown in Fig. 8 of the drawings. The strip 10 when thus arranged also forms a binding or finish for the upper edge of the neck of the bottle.

40 Any suitable form of closure may be provided for the neck or mouth of the bottle and in Figs. 3, 7 and 8 of the drawings the closure is shown in the form of a cap 11 which is adapted to be placed over the up-

45 per end of the bottle neck and to snugly fit around the sides of the same. In Fig. 12 of the drawings is shown a modified form of closure 12 which comprises a circular disk having a diameter slightly greater than 50 the outside diameter of the neck of the bottle and which is provided with a centrally disposed depressed portion 13 which forms a plug and is adapted to be inserted into the upper portion of the lining of the bottle 55 neck while the edges of the disk closely engage or fit the upper edge of the neck of the bottle as shown.

In Fig. 14 of the drawings is shown another slightly modified construction and arrangement of bottom 14 which is inserted 60 into the lower end of the body of the bottle similarly to the bottom 7 shown in Fig. 8 except that the bottom 14 is inverted or in a reverse position from the bottom shown 65 in Fig. 8 and sets up into the lower end of

the body of the bottle as shown. In the last form of bottom the downwardly projecting flanged edges thereof and the lower edges of the sides of the bottle are covered by a binding strip 15 of any suitable fabric, the edges of which are secured to the inner sides of the flanged edges of the bottom and the outer surface of the sides of the body. The strip 15 when thus arranged holds the bottom 14 in position and forms a finish for the lower edges of the body and bottom of the bottle. 75

The bottle when constructed as herein shown and described is preferably coated on the inner side or outer side or on both the inner side and outer sides with a suitable fluid proof solution which is preferably wax or paraffin and which renders the body and other parts of the bottle absolutely impervious to moisture and which covers all the joints and forms a sanitary and easily cleansed finish for the inner and outer surfaces of the bottle. I do not wish to be understood as confining the invention strictly to a bottle shaped container as shown in the drawings as it is obvious that a container of any shape or design may be constructed in accordance with the invention and in the manner described. 85 90

Having thus particularly described my 95 invention what I claim is:

1. In a container of the character described, a body formed from a suitable fabric and having its upper end crimped to form the upper portion and neck of the container, a casing engaged with the crimped upper portion of the body of the container, a second casing engaged with the outer side of the crimped neck of the container, a lining engaged with the inner side of the crimped neck, a bottom secured to the lower end of the body, and a closure having a removable engagement with the upper end of the bottle neck. 100 105

2. In a container of the character described, a body formed from a sheet of fabric bent into tubular form and having its edges and its upper portion crimped to form the upper portion of the body and neck of the container, a casing around the neck, a lining engaged with the inner surface of the crimped neck, a binding strip arranged over the upper ends of the crimped neck and the casing and lining thereof, and a bottom. 110 115 120

3. A container formed from a sheet of paper having secured thereto a woven fabric covering, said sheet of paper being bent into tubular form and having its edges tapered and overlapped to form a smooth joint and having its upper end crimped and pressed into shape to form the upper portion and neck of the container, casings arranged over the crimped upper portion and neck of the body, a lining engaged with the inner sur- 125 130

face of the neck, a bottom engaged with the lower ends of the body, and fluid proof coatings applied to the inner and outer surfaces of the container.

- 5 4. A container formed from a sheet of paper having secured thereto a woven fabric covering, said sheet of paper being bent into tubular form and having its edges tapered and overlapped to form a smooth 10 joint and having its upper end crimped and pressed into shape to form the upper portion and neck of the container, casings arranged over the crimped upper portion and neck

of the body, a lining engaged with the inner surface of the neck, a flanged bottom inserted into and secured to the lower end of the body, and means engaged with the bottom and outer sides of the lower end of the container to hold the latter in place. 15

In testimony whereof I have hereunto set 20 my hand in presence of two subscribing witnesses.

JOHN BALLANCE.
